CO-AXIAL RESISTIVE LOAD

Blossy D. Frederico, Cleveland, Ohio

Application March 18, 1955, Serial No. 495,129

4 Claims. (Cl. 333—22)

This invention relates to the art of electrical co-axial high frequency resistive loads employing compound dielectrics.

There have been numerous attempts to design a non-inductive termination for use as a "dummy load" for dissipating the radio frequency energy of transmitters. At first there was a non-inductive wire-wound resistor unit which however proved unsatisfactory as the frequency rate progressed into the higher range; such a unit did not act as a pure resistance but tended to become more and more reactive. Then came the resistors of the inked-on film type and the deposited-carbon type which satisfied the radio field temporarily but, as the rate of frequency moved higher and higher, neither did they behave as pure units. Tuning methods and the like were applied to these later units to cancel out the reactive portion of their characteristics at the higher frequencies but this method had many disadvantages, notably that of being a fixed frequency device which had to be readjusted for every change in frequency.

There were attempts to overcome these disadvantages, as for instance in the U.S. patent to Von Radinger No. 2,273,547, February 17, 1942, which used the film-type of resistor within an exponentially contoured horn fitted co-axially about the resistor element and which, to a limited extent, was a decided step towards the designing of terminations as "dummy loads" in the co-axial field of radio transmission and reception.

In the first attempts of such horn-type of device, air was used as the dielectric medium but, with the ever-increasing demand for units capable of dissipating greater and greater radio-frequency power, these devices had to be re-designed. Then there was attempted the same design with forced air-cooling but this did not greatly multiply the power-handling capabilities of the "dummy loads" and it was at this stage that a liquid was adopted to replace the air dielectric. The advantage of the liquid was utilized to increase the power-rating of the "dummy" (antenna) load, and this too was a notable step towards a more efficient heat-exchanging device. Then later there was added to such a device a secondary or auxiliary device to cool the dielectric liquid, which in turn would reduce the resistor temperature and thereby increase the power-handling capabilities of the termination ("dummy load"). This method consisted of coiled copper tubing with its coil immersed in the dielectric liquid outside of the horn enclosure. It is known by those versed in the design of horns for co-axial terminations that foreign objects and materials, not dictated by the design parameters, must be kept out of the dielectric space between the resistor and the horn enclosure; and it is also well known that water has tremendous cooling characteristics and, if used to its greatest advantage, may excel all other liquids in many cooling applications.

The prior design of heat exchanger, just referred to, depended upon the natural phenomenon of convection currents; that is, the dielectric liquid was set in motion by the rise in temperature of the dissipating element (resistor) of the horn assembly, the convection currents being a function of a change in fluid density that is produced by the rise in its temperature. In an attempt to further increase the power-rating of this type of "dummy

2

load," there was then added a pump for a more rapid cooling of the hot dielectric liquid which was pumped through the horn assembly and out into a tank where the water-cooling coils were located to cool the hot liquid, the cooled dielectric liquid being then returned to the horn.

It is the design of device, just referred to, that is currently used as a "dummy load" in the co-axial field to absorb the electrical energy, and the demand for higher and higher power-handling units has caused the designers to resort to larger resistor units in their horn designs; but this step is in the wrong direction for broad (frequency) band applications because of the attendant wave-guide effects. In view of the fact that the larger the diameter of the resistor, the larger the inside diameter of the horn must be, it follows that as the radio frequency is increased, the "dummy load" more likely will not function in the co-axial sense but will be excited more naturally into a wave-guide sense. However, it will be shown that this limitation can be overcome, even with resistors having as physically large size as are being presently used. The larger resistor in the present-day design does aid in increasing the power-handling ability of the unit but, as pointed out, it tends to reduce more and more its ability to be used at higher and higher frequencies in which of course the radio field is also interested. There is an important application for high-power loads at the higher frequency bands and perhaps the obvious solution would have been to use water directly as the dielectric field but this was not feasible with the existing facts. Water has a very high dielectric constant and this would have figured directly in the former design equation of the above-noted Von Radinger type of device which would have resulted in an impractical design limited to a narrow band because of wave-guide effects; and also it would have been so large in its physical proportions that hoisting means would have been required to move it about. The impracticality of such a design is further made apparent by noting the dielectric constant of water, which is 81 as compared with 1 for air. The physical proportions of such a design would be multiplied beyond practical limits if water alone were substituted for air as the dielectric medium in the design of a co-axial termination ("dummy antenna") in accordance with the teachings of the above patent to Von Radinger. However it will be shown herein that there is a unique solution to the foregoing limitations of water or air alone as a dielectric medium in co-axial terminations; and I will show that, by designing an instrument ("dummy load") with the small geometry advantages that are characteristic of air as a dielectric and the power-handling advantages of water as a dielectric, such a multiple or compound dielectric form of device would be a distinct and notable improvement over the present-day single dielectric form of device.

Accordingly, it is an object of my present invention to relieve the above-noted problems and complications in a non-inductive termination; and, more definitely, to design a resistive load in which there is widened frequency range and a high-power rating; to devise a practically reflectionless resistive load that is capable of dissipating large amounts of power; to avoid the necessity of employing auxiliary means of adjustment or tuning in such a device; to avoid the wave-guide effect in such a device; and to provide such a device that is within reasonable physical proportions.

More specifically, my present invention is directed to the accomplishment of the above-noted objects by designing a multiple-dielectric device in which there is included a logarithmic horn and in which there are utilized the small geometry advantages of air as a dielectric and the power-handling advantages of water as a dielectric, and in which the contour of the horn is arrived at by

means of an established equation for multiple dielectrics which I have discovered to be applicable for the accomplishment of this part of my present combination.

That is to say, I have discovered the applicability of a mathematical equation or relationship that makes possible a design using more than one dielectric medium within a horn form of outer enclosure. The horn in my present device takes on a more complex contour than that of the above Von Radinger patent because of the expanded equation that is employed instead of his simple relationship. It may be said that my expanded equation is multiple in its function and may be exploited to produce devices that have high-power ratings, broad-band operation, simplicity of construction, low-cost maintenance, reduced cost of fabrication, less bulk, etc.; and these briefly constitute the objects of my present invention.

Other objects will appear from the following description and claims when considered together with the accompanying drawing.

Fig. 1 is a perspective view of my present form of device;

Fig. 2 is a longitudinal sectional view thereof;

Fig. 3 is a transverse sectional view taken on line 3—3 of Fig. 2.

It is to be understood that the present form of disclosure is merely for the purpose of illustration and that there might be devised various modifications thereof without departing from the spirit of my invention as herein set forth and claimed.

The inventive thought in my present form of device is to design a broad-band co-axial ("dummy load") termination with direct water-cooling of the resistor element of the horn assembly. While other designers have used direct water-cooling to increase the power-rating, such devices have been narrow frequency-band units that require adjustments such as tuning, etc. None of the prior devices, so far as I am aware, has used the known mathematical equation for fashioning an enclosure that makes it possible to broad-band the device and also to get a high-power rating. By using the mathematical parameters derived, a horn enclosure can be designed with more than one dielectric material within the enclosure that coaxially surrounds the implanted resistor element, and my present form of device may be called a co-axial resistive termination of multiple or compound dielectrics with means of direct fluid-cooling.

If air is used as the complete dielectric material, it gives a small configuration to such a horn enclosure and a wide-band frequency range while water or other suitable liquids, if used as the complete dielectric material, makes for a large configuration but high-power rating and a limited frequency range. Now, my solution of the situation is to provide a compound dielectric with a cross section of water for a high-power rating and a larger cross section of air for a wide frequency range; and I have discovered that the use of mathematical parameters (see the equation below) for compound dielectrics in co-axial systems, makes such a design possible.

It will be noted here that my present form of invention includes a third dielectric material in addition to the air and water; namely, a dielectric tubing to carry the liquid (water) flow along the outside of the resistor element. The three dielectric materials are proportioned to give the maximum advantages; and the known dimensions of some of them, electrical and physical, are substituted in the equation in order to arrive at the size and hence the contour of the horn enclosure. It is important to state here that my final design will be a practically reflectionless (low voltage standing wave ratio) resistive co-axial load capable of handling large amounts of electrical energy over a wide-frequency range without using auxiliary tuning mechanism or adjustments. This "dummy load" can be used with calorimetry or with suitable current or voltage devices to measure electrical energy.

My present assembly in general consists of the electrical hollow form of resistance 1 which is surrounded by the co-axially spaced cylindrical shell 2 of dielectric material to provide a passage for water or other suitable liquid, and the co-axially arranged electro-conductive horn 3 which provides an enclosure for the air as another dielectric. The shell 2 may consist of plastic, Pyrex, glass or other suitable dielectric for piping a liquid. The cooling liquid (water for instance) enters through the hollow center of the resistor element 1 at the end corresponding to the small end of the horn 3 and flows along the length of the same in intimate contact therewith and out through vent holes 4a in the electro-conductive collar 4, suitably applied to the end of the resistor element 1, and along the inside of the dielectric tube 2 and is expelled from the openings 3a' in section 3a of the horn 3. The direction of flow of this liquid may be reversed. The back seal comprises flanges 5 and 6 of the horn sections 3 and 3a which bear against a flange of the dielectric duct 2 and are held by suitable fastening means as for instance screws and nuts. The seal at the other or front end of the device may be accomplished by the shoulder and threaded end of the collar 4 and a suitable electrical contact cylinder 7 threaded to mate with the threaded end of the collar 4 and to hold the flanged end of the dielectric duct 2 against the shouldered end of the collar 4. Clamp 8 holds horn 3 in contact with the resistor element 1 at the short-circuited end, as indicated in the present drawing.

30 The inside diameter of the horn 3 diminishes along its longitudinal axis and the contour of this horn is a function of the following equation which dictates the transverse diameters taken at incremental distances along the longitudinal axis of the assembly:

$$Z_0 = 138 \sqrt{\log \frac{b}{a} \left(\frac{\log \frac{d}{a}}{e_1} + \frac{\log \frac{t}{d}}{e_2} + \frac{\log \frac{b}{t}}{e_3} \right)}$$

in which Z_0 is the impedance at any plane transverse to the axis of the co-axial conductive horn 3 and the resistor element 1,

$$\log \frac{b}{a}$$

45 is the logarithm of the ratio between the diameters of the outer horn 3 and the resistance element 1,

$$\log \frac{d}{a}$$

50 is the logarithm of the ratio between the outer diameter of the liquid dielectric body and the diameter of the resistance element 1,

$$\log \frac{t}{d}$$

55 is the logarithm of the ratio between the outer diameters of the dielectric body 2 and the liquid dielectric body,

$$\log \frac{b}{t}$$

60 is the logarithm of the ratio between the diameter of the outer horn 3 and the outer diameter of the dielectric body 2, and e_1 , e_2 and e_3 are the coefficients of the three dielectric bodies—namely, the water, the body 2 and the air within the horn 3, respectively.

65 These incremental distances are stepped along the axis of the resistor element 1 and the value of Z_0 will vary accordingly at each transverse plane looking into the axis of the structure towards the end of the horn that diminishes to the point of intimate contact with the resistor element 1. As may be understood, the electrical input is at the end of the resistance element 1 corresponding to the larger end of the horn 3 and an outer electrical conductor will be connected to the larger end of the horn 3 which will be provided with suitable means for this purpose. Such connector means may be of the tapered

form or of the more practical radio-frequency stepped type (offset inner to outer construction).

The characteristic electrical impedance at a transverse plane looking back towards the diminishing end of the horn enclosure (i.e. Z_0), will have its maximum value (ohms) at the large or input end at plane A—A in Fig. 1, this being what may be called the start of the resistance material which may be in the form of deposited carbon or metal resistive film; and the value of Z_0 diminishes therefrom to zero at the plane of intimate contact of the horn section 3a with the resistor element 1. The resistive film of the resistor element 1 ends at the plane B—B and, for mechanical considerations, the electrical contact is carried a short distance beyond this point.

In solving the above equation for the diameter of the horn 3 at any given point along its longitudinal axis, we may assume the radial extent of the clearance or space for the flow of the liquid about the resistance element 1 and we may assume also the thickness of the dielectric shell 2. Then, knowing the diameter and length of the resistor element 1 and also its direct-current resistance per unit length, we may assume the resistance of the resistor element 1 which will be adopted as the impedance (ohms) at any given distance from the point where horn 3 joints shell 2 (plane B—B); and by substituting these known values in the above equation, there may be found the diameter of horn 3 at the point corresponding to that plane selected along the resistor 1. Thus the length and ohmic value of the resistor element 1 may determine the plane at which the equation is applied in each instance; and these planes should be selected at small intervals along the longitudinal axis of the resistor in order to obtain the best design for the horn 3. When these successive diameters for the horn have been determined, their outer ends will be connected and the form of the horn surface developed therefrom.

Another detail may be added to the design which will further improve the electrical performance at high frequencies; that is, the provision of longitudinal electro-conductive appendages 9 within and as integral parts of or in contact with the horn 3 to further discourage wave-guide effects. These tongues 9 need not run the entire length of the horn but only a short distance from the input or larger end thereof. In the present illustration there are shown four such appendages 9 spaced at ninety degrees about the longitudinal axis of the horn and that may be formed as integral parts thereof by the stamping process and they may extend for about one-fourth of the length of the horn 3, for instance. These appendages are so placed as not to interfere with the co-axial mode of operation but are so positioned as to co-operate in obtaining anti-wave-guide transmission.

Some of the details herein shown have the advantage of being self-compensating electrically; and it is to be understood that the mechanical or physical arrangement shown in the present drawing need not be the only way in which this combined unit may be fabricated, as above indicated.

There might appear to be an electrical upset in the horn enclosure at the point of the flanges 5 and 6, which is true physically but not electrically because the high capacitance represented by the indicated arrangement of the metallic faces of the flanges 5 and 6 functions to shunt the upset at higher frequencies, while at lower frequencies electrical continuity is sufficiently satisfactory not to produce undesirable electrical reflections. The operation of my present co-axial resistive termination is believed to be altogether dependable in both theory and practice.

My present invention possesses several marked advantages, some of which will be here briefly noted while still others will no doubt readily suggest themselves to those who are familiar with the art to which this invention relates. My present design simplifies the mechanical and electrical problems above referred to; the frequency

range is widened by use of the multiple or compound dielectric scheme in designing my resistive load which is practically reflectionless and is capable of dissipating large amounts of power. By providing a comparatively thin cross sectional flow of water, I have relieved the previous problem of the high dielectric constant of such a liquid; and I have discovered the applicability of a mathematical equation by which I am enabled to design a practical form of device. To repeat, I have devised a practically reflectionless resistive co-axial load that is capable of handling large amounts of electrical energy over a wide-frequency range and without having to resort to auxiliary tuning mechanism or adjustments.

In referring to the diameter of the logarithmic horn throughout the present description and claims, it is to be understood that I have in mind the inner diameter thereof, as mentioned in column 2, lines 14 to 19.

What I claim is:

1. An electrical resistor comprising an element, that is predominantly electro-resistive, and co-axially arranged separate and diametrically spaced tubular bodies surrounding said electro-resistive element and adapted to contain fluids of different dielectric coefficients, respectively, the outermost of said bodies being electro-conductive and being in the form of a logarithmic horn which is a function of said multiple dielectrics, and said horn having unitary means extending inwardly therefrom and being of an electro-conductive nature.

2. The same structure as recited in claim 1 hereof and in which said unitary means is in the form of a plurality of integral electro-conductive projections extending inwardly from said horn in spaced relation to each other thereabout.

3. An electrical resistor comprising a hollow element that is predominantly electro-resistive, a co-axially arranged cylindrical body of dielectric material arranged in spaced relation about said electro-resistive element, said electro-resistive element being open at one end and having means of communication at its other end with the space between the same and said cylindrical body, means for mounting said cylindrical body at its two ends upon said electro-resistive element, and an electro-conductive logarithmic horn mounted at its small end co-axially upon said cylindrical body and defining an air space within said horn, the larger end portion of said horn being provided with unitary inwardly extending projections of electro-conductive nature spaced thereabout.

4. An absorber of electrical energy comprising an element, that is predominantly electro-resistive, and co-axially arranged separate and diametrically spaced tubular bodies surrounding said electro-resistive element and adapted to contain two different fluids, respectively, one of which fluids is adapted predominantly to serve as a dielectric and the other of said fluids is adapted predominantly to serve as a thermal carrier, the outermost of said tubular bodies being electro-conductive and being in the form of a logarithmic horn whose specific shape is a function of said fluids, said electro-resistive element being of hollow form and open at one end thereof and having means of communication at the other end thereof with the corresponding end of the inner one of said tubular bodies, and the inner one of said tubular bodies having an opening at the other end thereof so as to permit passage of a fluid between said electro-resistive element and said inner tubular body.
